UNITED STATES PATENT OFFICE.

HERMANN LEMP, OF LYNN, MASSACHUSETTS, ASSIGNOR, BY MESNE ASSIGNMENTS, TO
GENERAL ELECTRIC COMPANY, A CORPORATION OF NEW YORK.

HYDROCARBON-BURNER.

No. 927,416.

Specification of Letters Patent.

Patented July 6, 1909.

Original application filed November 17, 1900, Serial No. 36,867. Divided and this application filed December 16, 1901. Serial No. 86,036.

To all whom it may concern:

Be it known that I, HERMANN LEMP, a citizen of the United States, residing at Lynn, in the county of Essex, State of Massachusetts, have invented certain new and useful Improvements in Hydrocarbon-Burners, of which the following is a specification.

The present invention is a division of my pending application Serial Number 36,867, filed November 17, 1900, which division is made at the requirement of the United States Patent Office under the provisions of Rules 41 and 42.

The object of the present invention is to provide a burner of the jet type, as distinguished from the Bunsen type, for kerosene or other hydro-carbon fuel, which is simple in construction and thoroughly reliable in its operation, and at the same time is capable of economically burning a large or a small amount of oil under wide ranges in pressure.

In the accompanying drawing, which illustrates an embodiment of my invention, is shown a burner in vertical section.

The burner comprises a flat base plate 1 which also forms the lower end of the boiler casing. Mounted on the plate is a tube 2 that forms a vaporizer. The vaporizer tube rises for a short distance at right angles to the base and is then inclined so that the upper end terminates at a point substantially over the nozzle. The lower end of the tube is supported by a socket that is secured to the upper side of the base plate 1. To the lower end of the vaporizer and its socket is connected a pipe 3 which extends to a suitable source of kerosene supply. The pipe 3 is connected to the coolest part of the vaporizer so that the tendency to burner disturbances, such as those due to pulsations and entrained oil, is largely reduced. It is evident that a considerable difference in temperature exists, when the apparatus is in operation, between the upper and lower side of the plate 1, especially when the parts are applied to an automobile. The upper end of the vaporizer is attached to a head 4, the latter being provided with two openings, one for the main vaporizer, the other for the tube 5, the latter being smaller and more easily heated than the main vaporizer, thus insuring the proper vaporization of the fuel prior to its delivery to the nozzle. It also assists in starting. The tube 5 is substantially V-

shaped with one long and one short leg, the 55 former being connected to the head 4 and the latter entering a socket carried by a tubular support mounted on the base plate. The head is subjected to great changes in temperature, it being heated practically red hot 60 when in service. The alternate heating and cooling of the parts soon makes a leaky joint with ordinary constructions, such as screw threaded unions, and permits the vapor which is working under high pressure to escape. I find it preferable to electrically weld the head to the tubes 2 and 5 so that they are in effect a single piece. As united the tubes 65 form two sides of a triangle, the advantages of which will appear hereinafter.

Burners have been heretofore constructed which were composed of a vertical vaporizing tube that was connected with a chambered metal piece occupying a horizontal plane, the said chambered piece also forming a part of 70 the vaporizer. With such a construction I have found that at times, owing to the pumping or pulsating action of the fuel, a "plug" of fuel will pass into the hottest part thereof and be immediately vaporized. This 75 will suddenly increase the pressure and the vapor will rush through the burner opening causing a pulsating action. If this takes place when the flame is greatly restricted, it will sometimes extinguish the flame, thus requiring an attendant to relight it. This objection is avoided by inclining the vaporizer tube, as in the present instance, so that the fuel will flow back into the pipe 3 instead of being retained in the vaporizer or in any 80 chamber intermediate the vaporizer and the nozzle. As an extra precaution the upper ends of the tubes 2 and 5 are arranged to overlap; in the present instance tube 5 extends some little distance into the enlarged 85 head 4 beyond the tube 2, so that, no matter if the fuel in liquid form momentarily flows into the tube 2, it will not have free access to the tube 5, as the projecting end of the tube 5 90 forms an obstruction.

Mounted on the base plate 1 is a tray 6 having two compartments or receptacles, one of which contains a body of asbestos 7 or some similar material used for starting the burner into operation, the other being used 95 to catch oil from the burner nozzle. The short leg of the V-shaped tube 5 extends near enough to the asbestos to be heated by

the flame therefrom, and while it is shown as being horizontal it may be otherwise arranged, the essential feature being to have it within the influence of the auxiliary burner

5 7. The long leg of the tube 5 and the upper end of the vaporizer tube 2, which are connected to the head 4, are shown as being straight, but they need not be mathematically so, since the essential features are to

10 have them near enough to the baffle plate to be acted upon by the flames in a manner to automatically vary the heating surface in accordance with the demand and cause the liquid fuel to be kept in its proper place.

15 15. Mounted in a support carried by the base is a tubular support 8; this support is provided at its upper end with a socket 9 for receiving the end of the horizontally extending portion of the vaporizing tube 5, and also

20 with a removable plug or nozzle 10 having a central fuel opening through which the needle 11 is adapted to project. It will be observed that the cross-section of the bore of the nozzle is very small compared to that of

25 the vaporizer. By reason of this arrangement a large supply of vapor is always on hand to feed the burner, and there is no danger of liquid fuel being entrained therewith. Between the body of oil in the vaporizing

30 tube 2 and the burner there is always maintained a body of vapor which is gradually superheated as it passes through the head and the tube 5. Accordingly when the temperature of kerosene is gradually raised to

35 the point of vaporization and then superheated there is less danger due to cracking or carbonization, as would be the case if the oil were suddenly brought into contact with red-hot metal. Thus the drainage receptacles

40 commonly used with burners of this class may be dispensed with. The wall surrounding the nozzle opening should be long enough to impart a definite direction to the vapor stream, since this will improve the operation

45 of the burner by causing the vapor to mingle with the proper amount of air at all times. It is to be remembered that this burner is intended to operate over wide ranges in pressure, hence the size of the nozzle opening

50 with respect to the cross-sectional area of the vaporizer, and especially the relation of the nozzle to the baffle plate, is of great importance. Owing to the use of a single opening with a high velocity vapor jet and horizontal

55 baffle plate of considerable area the tendency to back-fire is largely eliminated. The air does not mix with the vapor until after it strikes the baffle-plate, and in this manner my invention is differentiated from the Bunsen type of burner wherein the air is entrained with the vapor as it passes through a tube.

The portion of the tube 5 which enters the socket 9 extends horizontally for some little

60 distance over the trays and asbestos 7; this is

to insure the proper heating of the vaporizing tube for starting, and the tube as a whole insures that the fuel vapor shall be raised to a high temperature before it passes into the nozzle.

70 The needle 11 is carried by a spindle which makes a working fit with the bore of the tubular support 8. On the lower end of the support is a stuffing box 12 to prevent leaking of the vapor at that point. By actuating the 75 needle from a point below the nozzle opening and being careful that the needle itself does not extend above it the desired character of the flame can be preserved. Carried by the tubular support is a nut 13 that supports the tray. 80 Situated directly over the needle and mounted on the tube 5 is an adjustable baffling plate 14 having a horizontal baffling surface which is circular or disk-shaped to distribute the flames from the burner. The baffle plate 85 must present a smooth under surface of considerable area and be situated in close proximity to the end of the nozzle, so that the vapor jet issuing under high velocity will strike it and be deflected laterally in a manner to pick up the proper amount of air. If the baffle plate is too near or too far from the end of the nozzle the flame will be yellow and give off lots of smoke. If too far away, when the velocity of the vapor is very high, the 90 flame is liable to go out. The baffle plate is preferably, although not necessarily, supported by one of the vaporizing tubes. The vapor is deflected into the space surrounding the baffle plate and according to the processes 95 that take place in this space it may be divided into zones, viz: that area from the center of the baffle plate to a distance somewhat beyond its periphery in which the vapor combines with oxygen, and the area next beyond 100 and concentric therewith in which combustion occurs, and these for convenience may be termed the vapor carbureting zone and the combustion zone respectively. It is imperative that the carbureting zone be entirely free from obstructions, for the reason that an obstruction may act as an impediment to the deflected vapor, diminishing the force to such an extent that the vapor fails to incorporate enough air, and it ignites in the 105 space around the obstruction, if the latter be of sufficient size, and burns with a yellow smoky flame. For successful operation, the vapor after being once baffled must meet 110 with no interference between the time it leaves the baffle plate and the time it ignites, as any interference prevents the vapor from picking up sufficient air to enable combustion with the blue flame. Accordingly the position of the vaporizing tubes relatively to the 115 baffle plate is of particular importance. These are located so that sufficient space is afforded around the baffle plate to insure 120 complete carbureting of the vapor, and also its ignition before the burning vapor reaches 125 130

the vaporizing tubes. In other words the vaporizing tubes must be suitably remote from the periphery on the baffle plate and located in the zone of combustion. In practice the flames bend over the plate in such a manner that they strike the head 4 and keep it red hot while in service. I have found it preferable to make the baffle plate round and permit it to project beyond the plane of the vaporizing tube, because it will then distribute the vapor well and cause it to pick up the necessary amount of air to attain complete combustion. By experiment I have determined that the space between the end of the nozzle and the baffle plate should not be more than one and one half inches or less than three-fourths of an inch to attain the best results.

The needle 11 is not quite so large as the fuel opening in the plug 10, and is so designed that when inserted therein it will permit a certain amount of vapor to escape from the vaporizer and be burned, the amount of vapor thus consumed being sufficient to keep the parts hot, thereby insuring that the burner can be promptly started into operation, and this without objectionable odor. The needle constitutes a secondary regulator, and is not intended to regulate the supply of fuel to the burner under ordinary conditions of running, this being taken care of by a suitable system of regulation. Secured to the lower end of the needle is a lever 15 for raising and lowering it; this lever can be actuated in any desired manner, either for cleaning the burner or restricting the fuel opening. In addition to serving as a means for reducing the flame to a point below that due to the automatic regulating system, the needle also serves to keep the opening in the nozzle 10 clean.

It will be seen that by the arrangement described a burner is provided which is capable of furnishing the necessary heat to meet the given changes in conditions, and by a simple device such as a needle the flame can be reduced to such a point that it will keep the parts hot, and being within a suitable casing is not affected by gusts of wind.

The burner is intended more especially for kerosene, and operates successfully under wide variations in pressure. The burner is more especially intended for use on vehicles, and good practice dictates that the vapor pressure on the nozzle shall not be less than about five pounds per square inch when the vehicle is standing idle, or greater than fifty to sixty pounds when the vehicle is in full operation.

By reason of the parts being arranged as specified, the burner is capable of burning kerosene under a wide range of pressure, and with a blue flame which gives no odor. The arrangement of the parts also insures good combustion and freedom from soot. The flame, due to the vapor projected from the

nozzle under pressure, strikes the baffle plate and spreads laterally; this causes the flames to envelop the vaporizing tubes 2 and 5 to a greater or less extent and heat them to such a temperature as will maintain the fuel in vapor form. As the pressure on the burner is increased due to a suitable regulating mechanism to compensate for an increased demand for steam, the flames will envelop more of the vaporizer tubes, thus increasing their capacity for vaporizing fuel. In other words, as the burner pressure changes, more or less of the tubes will be brought into direct contact with the flames and their vaporizing effect will be automatically and correspondingly changed. When the pressure is low the portions of the tubes directly in line with the baffle plate will be the hottest, but as the pressure on the burner is increased by a suitable regulator, the heated part or zone will extend over a greater area. This last is due to the increased amount of vapor that is consumed. The tube 2 being inclined, a greater amount of fuel is exposed to the action of the flame at any given point than where the vaporizer is vertical. This is evident when it is considered that if the tube 2 were cut in a horizontal plane the end would appear as an ellipse.

In starting the burner into operation, the asbestos 7 is saturated with kerosene or some other inflammable material, and a lighted match is applied to the lower end of the downwardly-extending wick 16. The flame follows the wick up to the tray, and the fire spreads over the asbestos and heats the horizontal portion of the vaporizer tube 5. As soon as the vaporizer is heated to the proper temperature, any fuel which passes through the tube 2 into the tube 5 will be converted into vapor, and as the heat increases so will the temperature of the tubes. It is preferable to make the tube 5 of such a size and of such material that it is affected a little more quickly than is the tube 2. By this means the proper amount of heated vapor is always insured, and when the temperature materially increases, due to the large amount of fuel consumed, the effect of the vaporizers is increased.

In the construction of burners of the class to which this invention relates, the nozzle should be placed relatively near the baffle plate, and the velocity of the escaping vapor should be high.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States is:—

1. In a jet burner, the combination of a supporting base plate, a vaporizing tube which rises from the base and is inclined at an angle thereto, a second vaporizing tube which is smaller than the first and is also inclined to the base, the two tubes forming substantially a triangle, a head for uniting the adjacent ends of the tubes, a baffle plate, a nozzle situated under the baffle plate and in proximity thereto, a support for the nozzle, and a connection for conveying vapor from the vaporizers to the nozzle.
2. In a jet burner, the combination of a supporting base plate, a vaporizing tube which rises from the base and is inclined at an angle thereto, a means for supplying oil to the vaporizer from the under side of the base plate, a nozzle, a second tube smaller than the first, comprising an inclined portion and a part extending at an angle thereto which is connected to the nozzle, and a baffle plate having a smooth under surface for causing the flames to spread laterally and embrace the inclined tubes to a greater or less extent.
3. In a jet burner, the combination of a supporting base plate, a vaporizing tube rising from the base and inclined at an angle thereto, a socket in which the tube is seated, a means for supplying oil to the coolest point in the tube, a nozzle, a second tube smaller than the first, comprising one portion that is inclined to the base and a second portion that connects the first with the nozzle, a heating device that is operatively arranged with respect to said second portion, a baffle plate, provided with a smooth under surface arranged to spread the vapor, and a support for the nozzle that is carried by the base plate.
4. In a jet burner, the combination of a base, a vaporizing tube which rises from the base and is inclined at an angle thereto, a connection that is attached to the vaporizer at a point under the base for supplying liquid fuel thereto, a horizontal disk-shaped baffle plate which extends beyond the plane of the vaporizing tubes and is situated in close proximity to the nozzle for spreading the vapor and causing it to pick up the proper amount of air, a nozzle having an opening for discharging vapor against the baffle plate, a second inclined vaporizing tube, the said tubes forming a triangle, and a head for receiving the ends of the tubes and maintaining them in a definite angular relation, the said head being situated in line with the nozzle opening.
5. In a jet burner, the combination of a base plate, a vaporizing tube mounted thereon which extends vertically at right angles to the plate for a short distance and then inclines toward the center of the burner, a second vaporizer tube which is smaller than the first and is inclined to the base plate for a certain portion of its length and parallel

therewith for a certain other portion, a nozzle, a head which unites the tubes and forms the apex of a triangle, and a starting or auxiliary burner operatively located with respect to the horizontal portion of the vaporizer.

6. In a jet burner, the combination of a base, a vaporizing tube, mounted thereon at an angle, a tubular support mounted on the base and provided with a socket having two openings, a head which is attached to the vaporizer, a second vaporizing tube which is secured to the head at one end and enters one opening in the socket at the other, and a detachable nozzle which is seated in the second opening and contains a straight bored fuel opening.

7. In a jet burner, the combination of a base plate, a vertically extending tubular support having a socket, a detachable nozzle mounted in the socket, a needle mounted on a stem and located in the support, the needle and nozzle opening making a loose fit so that the supply of vapor cannot be entirely shut off, a V-shaped vaporizing tube having a long and short leg, a starting or auxiliary burner for heating one of said legs, a second inclined vaporizing tube larger than the one first mentioned, and a baffle plate which is adjustably mounted on the inclined portion of one of the vaporizing tubes.

8. As an article of manufacture, a jet burner comprising a base plate 1, a pair of vaporizing tubes 2 and 5 one of which is more easily heated than the other and which rise from the base and are inclined toward each other at their upper ends, a head 4 having openings to receive the overlapping ends of the tubes, the head being so arranged that the tubes extend into it at an angle and are held in an overlapping position so as to prevent pulsation, a baffle plate 14, a nozzle 10 having an opening situated in close proximity to the baffle plate, and a needle 11 which is arranged to reduce the amount of vapor delivered by the nozzle but not to interrupt it.

9. A burner comprising an inverted V-shaped vapor-carrying conduit which passes through the combustion zone of the burner and is formed of two portions inclined outwardly from the center of the burner, a pipe for supplying liquid fuel to one portion of the conduit, a centrally located head uniting the two portions, means in the head which serves to prevent liquid fuel from passing from one portion of the conduit to the other during normal operation, a nozzle connected to the discharge end of the conduit and arranged beneath the head which discharges a stream of fuel vapor at relatively high velocity, and a baffle-plate located a short distance above the nozzle and between it and the head so that the stream of vapor strikes the plate and is deflected outwardly to cause

combustion to occur in the zone surrounding the periphery of the plate.

10. A burner adapted to work under relatively high pressure, which comprises a vapor-carrying conduit having symmetrically inclined portions of differential bore, a nozzle attached to the portion of smaller bore and discharging a stream of vapor under relatively high velocity, a baffle plate arranged intermediate the inclined portions of the conduit which receives and spreads the vapor from the nozzle prior to ignition and deflects it toward the conduit after which ignition takes place, a base upon which the burner is mounted, the said base being subjected to different temperatures on opposite sides, and a connection for supplying fuel to the conduit from the cooler side of the base.
20. 11. A burner comprising a liquid fuel receiving tube of large bore for vaporizing the fuel, a superheating tube of relatively small bore whose receiving end projects into the other tube and tends to prevent liquid fuel from passing into the superheating tube, a nozzle to which the vaporized fuel is delivered by said superheating tube, and a baffle plate arranged in co-operative relation to the nozzle and intermediate both tubes with its periphery entirely separated therefrom to afford an annular zone of combustion around the plate.

30. 12. A burner, comprising a conduit having two inclined portions of large and small bores and a horizontal portion terminating at a line bisecting the angle between the inclined portions, the receiving end of the portion of small bore extending into the portion

of large bore, a nozzle at the end of the horizontal portion adapted to deliver a jet of fuel vapor substantially in the direction of the juncture of the two inclined portions of the conduit, and a baffle plate disposed centrally above the nozzle for receiving the jet therefrom and arranged between the inclined portions of the conduit with its periphery separated therefrom.

13. In a burner, the combination of a base, an inverted V-shaped fuel vaporizing conduit which passes through the combustion zone of the burner, comprising portions inclined toward each other and forming an apex centrally located above the burner, and in which the fuel is vaporized by the heat of said zone, one of said portions being supported on the base receiving liquid fuel at its lower end and adapted to contain vaporized fuel at its upper end, the other portion receiving vapor from the first portion and further heating it, a baffle-plate supported below the apex of the conduit and surrounded by a space forming carbureting and combustion zones into which it deflects the fuel vapor, a nozzle located in close proximity to the baffle-plate containing an orifice, which discharges vapor at relatively high velocity against the baffle-plate to be deflected laterally thereby, and means for feeding liquid fuel from a source of supply to the vaporizing conduit.

In witness whereof I have hereunto set my hand this 12th day of December, 1901.

HERMANN LEMP.
